RAIL LUBRICATOR

Henry J. Perazzoli, Philadelphia, Pa., assignor to
 Railway Track-work Company, Philadelphia,
 Pa., a corporation of Pennsylvania

Application March 27, 1936, Serial No. 71,081

4 Claims. (Cl. 184—3)

This invention relates to a rail lubricator and is especially concerned with a lubricating device for a rail of the type having a guard providing a groove adapted to receive the wheel flanges as they travel on the rail. Still more specifically the invention is concerned with a lubricator especially adapted for use on curved rail of the type mentioned, so as to overcome undesirable wear not only of the rails themselves but also of the wheel flanges, and with the further object in view of overcoming the noise frequently produced, for example, by street railway cars turning corners.

The nature, objects and advantages of the invention will appear to best advantage after consideration of certain problems encountered and the manner in which attempts have heretofore been made to overcome certain of these problems and conditions.

In many instances it has been customary to provide for lubrication of curved rail of street railways by manually spreading lubricant within the groove of the rail at frequent intervals. This, of course, is obviously laborious and in addition it is frequently impracticable to accomplish the manual lubrication often enough to insure against noise and excessive wear.

It has also been proposed to employ a mechanical device, usually positioned below the street level or adjacent to the rail, for delivering lubricant to the rail groove. Certain prior devices of this type have adopted a heavy oil as the lubricating medium and have made provision for the delivery of this oil to the base of the groove, the intention being that the wheel flanges shall carry this lubricant along the rail and thus spread it, particularly around the curved portions.

This prior type of oil lubrication has been proven to have serious disadvantages and to be comparatively ineffective. In the first place, delivery of the oil to the bottom of the rail groove has not resulted in effective lubrication of the side faces of the groove, particularly the side face of the guard for the rail, and I have found that to effectively accomplish the lubrication in question it is highly desirable to provide thorough distribution and spreading of the lubricant on the inner side face of the rail guard.

Another disadvantage of the prior oil delivery to the base of the rail groove is that the delivery passages constantly become clogged with dirt, grit, etc. Assume for a moment that a stone has become lodged in a rail groove. Upon the passage of a wheel over the stone, the flange will, of

course, disintegrate the stone and when this occurs adjacent an oil delivery passage the result is that the passage becomes badly jammed and, therefore, ceases to perform its intended function. Still further, it is normally to be expected that an accumulation of grit and dirt will occur in the base of the rail groove. This accumulation obviously mingles with the lubricant delivered to the base of the groove and the result is that the wheels shortly act to distribute what, in effect, constitutes a grinding compound which, at times, has been shown to be of such character as to produce more rapid wear than would occur in the complete absence of lubrication.

Still another difficulty heretofore encountered resulted from undesirable splashing of oil especially in warm weather, the result being that oil was caused to come in contact with the rims of the wheels which ride on the rail proper and as a result in contact with the brake shoes. In consequence, braking force as well as traction is lost.

With the foregoing and other problems in view, the present invention provides for utilization of a grease, preferably of the graphite type, which grease is delivered, by means hereinafter to be described, through a passage having its outlet end opening through the inner side of the rail guard at a point spaced appreciably above the bottom of the rail groove. Preferably this lubricant is delivered at a point adjacent the top of the rail guard and I have found by test that on curved track, the wheel flanges coming in contact with the inner side face of the guard effectively distribute the lubricant and further that this lubricant adheres to the surface in a manner to provide a high degree of lubrication even when only a small quantity of the lubricating medium is delivered within a given time or for each vehicle which passes.

A further object of the invention is concerned with the provision of a distribution groove formed in the inner side face of the guard in a special manner to promote effective distribution of the lubricant under the influence of the contact of the wheel flanges with the guard.

Another object of the invention is involved in overcoming various of the other difficulties mentioned above, it being noted particularly that lubrication in accordance with the present invention virtually eliminates any substantial mixture of dirt, grit, or the like with the lubricant. The grinding action heretofore encountered is therefore obviated. In addition the improved arrangement avoids the difficulties resulting from

contact of the lubricant with the rim of the wheel. In addition to the above the invention has in view the provision of novel means for the delivery of the graphite or similar grease, which means comprise a pump cylinder and a pump plunger, the latter of which is actuatable by the flanges of the wheels as they travel on the rails and operates to deliver a charge of lubricant for each wheel passing.

10 Still further it is an object of the invention to arrange the pump operating element in position to be actuated by the edge of the wheel flanges and to arrange the delivery opening for the lubricant in the side face of the guard in position to cooperate with the side face of the wheel flanges in spreading the lubricant. In this connection, the spacing of the lubricant outlet from the pump actuating element is such that the flange of the wheel in passing along the rail reaches the lubricant outlet at approximately the same time that the charge of lubricant is expelled from the outlet.

15 How the foregoing objects and advantages are attained, together with others which will occur to those skilled in the art, will be more apparent from a consideration of the following description making reference to the accompanying drawings, in which:—

20 Figure 1 is a side elevational view of a portion 30 of a rail, showing portions of the improved lubricator associated therewith;

25 Figure 2 is a top plan view of the features shown in Figure 1 and further illustrating a lubricant reservoir; and

30 Figure 3 is a vertical sectional view taken substantially as indicated by the section line 3—3 on Figure 1.

35 In all views, the reference letter R indicates the rail. For installation purposes, a box 4 is preferably built below the level of the street (when the equipment is applied in street railway practice), the top of the box being approximately at the same level as the upper edge of the rail. Within the box a reservoir 5 for the grease 40 is provided and the reservoir is equipped with any suitable means such as a plug 6 for recharging or refilling, which may be accomplished by removal of the lid 7; the lid is desirably fastened in place by means of a locking device including locking elements 8 and actuating disk 9 therefor which latter are operable as by means of a key which may be inserted through the lid to rotate the disk 9.

45 The mechanism further includes a pump unit 50 P which is nested between the rail guard 10 and one of the base flanges 11, the unit being desirably supported on a flange 11 as by a wedge plate 12 which may conveniently be welded to the flange. The rail proper, shown at 13 serves to carry the wheels of the vehicles as they pass and as clearly shown in Figure 3 the flange F of the wheel W rides in the groove formed between the rail part 13 and the guard 10.

55 In addition to the wedge 12 which may be made of different thicknesses in order to accommodate the device to rails of different heights, the pump unit includes a cylinder 14 which is fastened to the wedge 12 by means of studs and nuts 12a. In addition, a bolt 12c may be inserted 60 through the base of the cylinder and threaded into the wedge 12. The base of the cylinder is provided with slots 12b which provide for movement of the unit into position under the head of the rail in a lateral direction and also for withdrawal of the unit in the same way.

65 A plunger 15 is adapted to move within the cylinder, a packing gland 15a being provided at the upper edge of the cylinder so as to prevent lubricant from coming out of the top end of the cylinder on the downstroke of the plunger. The plunger projects upwardly from the cylinder through a hole drilled through the rail at the base of the groove therein. The upper end of the plunger thus serves as an actuating element for the pump, this upper end being depressed by a 70 flange when a wheel moves past the point where the pump unit is located. As clearly seen in Figure 3, the plunger 15 is constantly urged upward by means of a spring 16.

75 A pair of connections communicate with the lower end of the cylinder 14. One of these, 17, extends to the reservoir 5 and serves for the transfer of lubricant from the reservoir to the pump cylinder. The other connection, shown at 18, serves to deliver lubricant from the pump 20 cylinder to the rail in the manner referred to more fully hereinafter.

80 Connection 17 is provided with a casing 19 in which a ball-check valve 20 is located for the purpose of closing the pipe 17 on the downstroke 25 of the plunger 15. Check valve 20, however, is opened under the influence of the upstroke of the plunger and this, of course, draws the charge of lubricant from the reservoir 5 into the bottom end of the cylinder 14.

85 The connection 18 is provided with a casing 21 for a ball-check valve or equivalent device 22 which is inverted with reference to the device 20 in the sense that upon the upstroke of the plunger 15 the check valve 22 is closed and upon the downstroke thereof the ball 22 is forced from its seat to permit the delivery of a charge of lubricant through the pipe 18 to the rail.

90 The degree of movement of the plunger, i. e., the pumping stroke thereof is preferably adjustably limited so as to provide control of the charge of lubricant delivered on each stroke. For this purpose the plunger 15 is provided with an abutment, conveniently formed by recessing the side of the plunger as at 23 so as to produce 45 a shoulder 24 (see Fig. 1). The abutment shoulder (24) cooperates with an adjustment disk or the like 25 which is threaded on a shaft 26 positioned and spaced in parallel relation in respect to the plunger 15. A lock nut 25a is provided to secure the disk 25 in adjusted position. The threaded shaft 26 is secured at its lower end to the cylinder 14. With this construction the upward movement of the plunger out of the cylinder is adjustably limited and as a result 50 the effective pumping stroke is thus controllable. 55

95 The delivery end of the pipe 18 communicates with a passage 27 which is drilled through the rail guard 10 in such position that its outlet end opens through the inner side face of the rail guard 10 toward the upper edge of this side face. This passage, moreover, is drilled at an angle, as shown in Figure 1, inclined in the direction in which the cars travel on the rail (see arrow D in Fig. 1). The outlet end of passage 60 27 is located approximately at the same level as the upper surface of the rail 13. As best seen in Figures 1 and 2, a distribution groove 28 is provided in the side face of the guard 10, this groove being extended along the rail from the 65 outlet opening of passage 27 along the upper edge of the guard 10 in the general direction of inclination of the passage 27 so as to cooperate with the wheel flanges passing along the rail 70 in the direction of the arrow D in spreading 75

the lubricant. Toward its end the groove 28 is curved downwardly somewhat as shown at 28a, this for a purpose to be referred to more fully hereinafter.

5 In operation, when the wheel W passes over the actuating plunger 15 of the pump, the wheel flange F depresses the plunger and this forces a charge of lubricant through the check valve 22 and through the pipe 18 for discharge at the 10 inner side face of the guard 10. In connection with the operation, it should also be noted that there is a certain time lag in the delivery of a charge of lubricant under the influence of actuation of the pump. In other words, a short period 15 of time elapses from the time the pump plunger is depressed until the time that the lubricant is discharged out of the passage 27. In accordance with the invention, the spacing of the outlet of passage 27 beyond the pump plunger 15 is such 20 that, with a car travelling over the rail at the average speed for that particular portion of the track, the wheel flange reaches the outlet point substantially at the same time as the lubricant charge. This is important since the wheel thus 25 carries away at least a substantial portion of the charge of lubricant delivered and, in turn, this helps to avoid accumulation of lubricant in the base of the rail groove.

The foregoing represents the preferred arrangement in instances where vehicles normally pass over the trackway in only one direction. It will be understood, however, that the equipment is also useful in lubricating rails where vehicles 30 pass over the tracks in both directions.

35 Movement of the wheel along the rail results in spreading or distribution of the discharged grease by contact of the inside face of the wheel flange F with the inner face of the guard 10. This contact tends to force the grease along the length of the 40 groove toward the far end thereof, at which the groove is turned downwardly. The grease is thus directed somewhat downwardly so that a band of appreciable width becomes thoroughly lubricated. It will be noted, however, that this is accomplished 45 without substantial mixture of the grease with dirt or grit, which of course accumulates in the bottom of the rail groove, and further without danger of lubricant splashing on the wheel rim or on the brake shoes.

50 The mounting of the pump unit P on the base flange 11 in the manner described is of advantage since this mounting avoids the necessity of drilling through the web of the rail or tearing up the street at the outer side of the rail (to the left in 55 Fig. 3) when making an installation.

The foregoing arrangement, I have found, materially improves the effectiveness of the lubrication and substantially completely overcomes a number of serious difficulties heretofore encountered.

I claim:

1. A device for lubricating a rail including, in combination with a rail having a groove to receive wheel flanges, a lubricant passage formed in a 60 side face of the rail groove, means for spreading lubricant on the side face of the rail groove including a groove formed in said side face, and pump means for delivering lubricant to said passage including an operating element positioned in 65 the base of the rail groove, said operating element

and the spreading means being actuatable by contact with the periphery of a wheel flange and the side face of a wheel flange, respectively, during passage of a wheel along the rail, and the operating element being offset from the spreading means 5 lengthwise of the rail in a direction in advance of the spreading means with respect to the normal direction of travel on the rail.

2. A device for lubricating a rail including, in combination with a rail having a groove to receive 10 wheel flanges, a lubricant passage formed in a side face of the rail groove, and pump means for delivering lubricant to said passage including an operating element positioned in the base of the rail groove, said operating element and the outlet 15 opening of said passage being positioned for cooperation, respectively, with the periphery of a wheel flange and with the side face of a wheel flange, during passage of a wheel along the rail, and said outlet opening being spaced beyond the operating 20 element, with respect to the direction of travel of the wheel, a distance such that, at an average rate of travel of the wheel on the rail, the wheel flange reaches said outlet opening substantially 25 at the same time as the charge of lubricant delivered by the pump means as a result of actuation of the operating element by said wheel.

3. A device for lubricating a rail including in combination with a rail having a groove to receive 30 wheel flanges, a lubricant passage formed in the side face of the rail groove, pump means for delivering lubricant to said passage including an operating element positioned in the base of the rail groove, said operating element and the outlet 35 opening of said passage being positioned for cooperation, respectively, with the periphery of the wheel flange and with the side face of a wheel flange, and said outlet opening being spaced beyond the operating element with respect to the direction of travel of the wheel on the rail, and a lubricant distribution groove formed in a side face of the rail groove, communicating with the outlet opening of said passage toward one end and extending therefrom in a direction away from the operating element for the pump means. 45

4. A device for lubricating a rail including, in combination with a rail having a groove to receive wheel flanges, a lubricant passage formed in a side face of the rail groove, pump means for delivering lubricant to said passage including an operating 50 element positioned in the base of the rail groove, said operating element and the outlet opening of said passage being positioned for cooperation, respectively, with the periphery of a wheel flange and with the side face of a wheel flange, during 55 passage of a wheel along the rail, and said outlet opening being spaced beyond the operating element, with respect to the direction of travel of the wheel, a distance such that, at an average rate of travel of the wheel on the rail, the wheel flange 60 reaches said outlet opening substantially at the same time as the charge of lubricant delivered by the pump means as a result of actuation of the operating element by said wheel, and a lubricant distribution groove formed in a side face of the 65 rail groove, communicating with the outlet opening of said passage toward one end and extending therefrom in a direction away from the operating element for the pump means.
